E. J. McNEILL

JOURNAL JACK BLOCK AND WHEEL CLAMP

Filed March 10, 1923

UNITED STATES PATENT OFFICE.

EDMUND J. McNEILL, OF BALTIMORE, MARYLAND.

JOURNAL JACK BLOCK AND WHEEL CLAMP.

Application filed March 10, 1923. Serial No. 624,187.

To all whom it may concern:

Be it known that I, EDMUND J. McNEILL, a citizen of the United States, residing at Baltimore, in the State of Maryland, have ⁵ invented a certain new and useful Improvement in Journal Jack Blocks and Wheel Clamps, of which the following is a full, clear, and exact description.

This invention is in the nature of an improvement on the journal jack-block and wheel-clamp patented to Charles O. Vest, June 21, 1921, No. 1,382,332.

The invention consists in a journal jack-block and wheel-clamp in which the clamp ¹⁵ is freely movable in the direction of its length in the jack-block or base-piece and is provided with ratchet teeth adapted to engage complementary portions on the base-piece to hold the clamp in adjusted position, ²⁰ as I will proceed now to explain and finally claim.

In the accompanying drawings illustrating the invention, in the several figures of which like parts are similarly designated, ²⁵ Figure 1 is a perspective view. Fig. 2 is a partial section and elevation illustrating the invention in use. Fig. 3 is a longitudinal section. Fig. 4 is a longitudinal section of one end of the base-piece with the wheel-³⁰ clamp removed. Fig. 5 is a front elevation, and Fig. 6 a side elevation of the wheel-clamp detached.

As in the patent referred to, so here, 1 is a car wheel, having the ordinary or any approved rim 2. 3 is a portion of an ordinary or approved axle-box. 4 is a cross section of a track rail. 5 is any ordinary or approved lifting-jack.

The implement of the present invention ⁴⁰ comprises a jack-block or base-piece 6, which may be made of metal and supplied at one end with a suitable handhold 7 for handling the implement. At its opposite end this base-piece is provided with an outwardly ⁴⁵ inclined upright 8 slotted centrally at 9 and provided with the upwardly flaring grooves 10 extending from top to bottom. The horizontal portion of the base-piece is provided with a stop-lug 11, and the upper portion of ⁵⁰ the upright is provided with any suitable number of teeth 12 extending transversely across the slot 9 and offset from the grooves 10.

The wheel-clamp 13 is an inclined structure, complementary to the inclination of the

upright 8, and having the shank portion 14 adapted to fit in the slot 9 and having any suitable number of laterally projecting lugs ⁶⁰ 15 adapted to engage the grooves 10, and also having a recess 16 adapted to cooperate with the stop-lug 11 to limit the downward movement of the wheel-clamp in the upright. The face of the shank is provided with ratchet teeth 17 complementary to the ratchet teeth 12 of the upright and adapted to engage the latter to hold the wheel-clamp in ⁶⁵ adjusted position with relation to a wheel with which it is engaged, as indicated in Fig. 2. The wheel-clamp is arranged in the upright loosely so as to have perfect freedom of longitudinal movement and also so as to be capable of movement toward and from the teeth 12 to engage and disengage ⁷⁰ such teeth. The wheel-clamp is held from escape upwardly from the upright by any ⁷⁵ suitable stop, as for example a screw 18. Of course this screw may be replaced by a rivet or other device. The upper end of the shank 14 has the outwardly projecting lip ⁸⁰ 19 shaped to conform, at least approximately, to the back of the rim 2 of the wheel as shown in Fig. 2, to serve as a hold-down for the wheel while the journal box is being jacked up.

Not only does the present invention differ from the structure shown in the patent referred to with respect to the construction, arrangement and operation of the wheel-clamp, but it also differs in the strengthening of the upright of the base-piece by connecting its upper ends by means of the cross-piece 20 on the back of which are located the teeth 12. This cross-piece is offset so that in conjunction with the slot and tapering grooves there will be plenty of room for ⁸⁵ the play of the wheel-clamp in adjusting it. ⁹⁰

Variations in details of construction and arrangement of the parts are considered to be permissible within the principle of the invention herein claimed. ⁹⁵

What I claim is:—

1. A journal jack-block and wheel-clamp, having a base-piece to support a lifting-jack, said base-piece provided at one end with an outwardly inclined upright having a longitudinal slot and upwardly tapering grooves adjacent to said slot and a suitable number of transversely arranged teeth crossing said slot, a correspondingly inclined wheel-clamp having a shank provided with lateral ¹⁰⁰ ¹⁰⁵ ¹¹⁰

5 lugs adapted to engage the grooves, a wheel-engaging lip, and transversely arranged teeth adapted to cooperate with the teeth on the upright to hold the wheel clamp in adjusted position.

10 2. A journal jack-block and wheel-clamp, having a base-piece to support a lifting-jack, said base piece provided at one end with an outwardly inclined upright having a longitudinal slot and upwardly tapering grooves adjacent to said slot and a suitable number of transversely arranged teeth crossing said slot, a correspondingly inclined wheel-clamp having a shank provided with lateral lugs 15 adapted to engage the grooves, a wheel-engaging lip, and transversely arranged teeth adapted to cooperate with the teeth on the upright to hold the wheel clamp in adjusted position, said base-piece having a lug projecting into the slot and said shank having a recess to cooperate with said lug to stop the descent of the wheel-clamp.

15 3. A journal jack-block and wheel-clamp, having a base-piece to support a lifting-jack, 20 said base-piece provided at one end with an outwardly inclined upright having a longitudinal slot and upwardly tapering grooves adjacent to said slot and a suitable number of transversely arranged teeth crossing said 25 slot, a correspondingly inclined wheel-clamp having a shank provided with lateral lugs adapted to engage the grooves, a wheel-engaging lip, and transversely arranged teeth adapted to cooperate with the teeth on the 30 upright to hold the wheel clamp in adjusted position, said base-piece having a lug projecting into the slot and said shank having a recess to cooperate with said lug to stop the 35 descent of the wheel-clamp, and said shank

having a stop to prevent the upward escape 40 of the wheel-clamp.

4. A journal jack-block and wheel-clamp, having a base-piece to support a lifting-jack, said base-piece provided at one end with an outwardly inclined upright having a longitudinal slot and upwardly tapering grooves adjacent to said slot, said upright provided with a cross-piece bridging the slot and having a suitable number of transversely arranged teeth, and a wheel-clamp slidably mounted in said grooved upright within the slot and provided with transverse teeth adapted to engage the teeth on the cross-piece.

5. A journal jack-block and wheel-clamp, having a base-piece to support a lifting-jack, said base-piece provided at one end with an outwardly inclined upright having a longitudinal slot and upwardly tapering grooves adjacent to said slot, said upright provided with an offset cross-piece bridging the slot and having a suitable number of transversely arranged teeth, and a wheel-clamp slidably mounted in said grooved upright within the slot and provided with transverse teeth adapted to engage the teeth on the cross-piece, the tapering grooves and the offset cross-piece affording ample room for the movement of the wheel-clamp into and out of engagement with the teeth on the upright.

In testimony whereof I have hereunto set my hand this 9th day of March, A. D. 1923.

EDMUND J. McNEILL.
